TOOL FOR APPLYING ANIMAL IDENTIFICATION TAG

Harley E. Nichols, Jr., Hardwick, Vt., assignor to
C. H. Dana Company, Inc.

Filed Mar. 4, 1971, Ser. No. 121,238

Term of patent 14 years

Int. Cl. D8—05

U.S. Cl. D8—14

FIG. 1 is a front view of a tool for applying an animal identification tag showing my new design;

FIG. 2 is a top view thereof;

FIG. 3 is a left side view thereof; and

FIG. 4 is a partial front view thereof, the broken line showing of the identification tag being for illustrative purposes only.

The undisclosed end is flat and plain.

I claim:

The ornamental design of a tool for applying animal identification tag, as shown and described.
